UNITED STATES PATENT OFFICE.

ALEXANDER G. SIMPSON, OF ARCADIA, MISSOURI.

FASTENER FOR DOORS, WINDOWS, GATES, &c.

SPECIFICATION forming part of Letters Patent No. 296,469, dated April 8, 1884.

Application filed August 20, 1883. (No model.)

To all whom it may concern:

Be it known that I, ALEXANDER GRAY SIMPSON, of Arcadia, Missouri, have made a new and useful Improvement in Door, Gate, and Window Fasteners, of which the following is a full, clear, and exact description, reference being had to the annexed drawings, making part of this specification, in which—

Figure 1 is a view in perspective of the improved fastener; Fig. 2, a front elevation, showing the device as when the door is fastened; Fig. 3, a section on the line 3 3 of Fig. 2; Fig. 4, a front elevation, showing the device as when the door can be opened; Fig. 5, a section on the line 5 5 of Fig. 4.

The same letters of reference denote the same parts.

This improvement is adapted either to doors, gates, or window-sashes.

It consists, substantially, of a journal fastened to the fixed part of the structure—that is, the door-jamb, gate-post, or upper sash—and provided with an adjustable arm, the journal and arm being so relatively constructed as to enable the arm, when upon one part of the journal, to be rotated upon the journal, and thereby enable the door, gate, or sash to be opened, but when slipped onto another part of the journal to be prevented from rotating, and, in consequence, to become an obstacle to the opening of the door, gate, or sash.

A desirable mode of carrying out the improvement is shown in the drawings, where A represents the fixed part of the structure—that is, in case of a door it would be the door-jamb, in case of a gate it would be the gate-post, and when the device is used as a sash-fastener the part A would be the upper sash. B represents the part which opens—that is, the door, gate, or lower sash. C represents what I term the "journal," which is attached to the fixed part A in any suitable manner, so that the arm D can be operated as described. 45 A simple and sufficient mode is to provide the

journal with points c c, which are extended and driven into the part A as if inserting a staple, and as shown in Figs. 2, 3, 4, 5. A portion, c', of the journal is rounded to enable the arm D to turn thereon. Another portion, c'', of the journal is squared or provided with a shoulder, to prevent the arm, when upon that part of the journal, from turning. When it is desired to leave the gate, door, or sash free, the arm is allowed to remain on the part c' of the journal, as in Figs. 4, 5, and when the door, gate, or sash is opened the arm D yields and turns upon the part c' of the journal. When it is desired to lock the door, gate, or sash, the arm D is slipped onto the part c'' of the journal, as shown in Figs. 1, 2, 3. This prevents the arm from being rotated, and the door, gate, or sash cannot be opened.

I do not wish to be confined to the precise forms shown at c' c'' in relatively shaping the journal and arm. For instance, instead of the square form shown in part c'' of the journal, a spline or any suitable shoulder can be employed, which, when the arm D is slipped onto it, will come against a corresponding shoulder in the eye d of the arm and prevent the arm from turning, and the part c' of the journal need not necessarily be round, provided the eye d can turn on the part c'. The requisite is that the two parts c' c'' and the eye d of the arm D shall be so relatively constructed as to enable the arm to turn upon the part c' and be prevented from turning when upon the part c''.

I claim—

The combination, in a fastener, of the journal C and the arm D, said journal having the two parts c' and c'', and said arm having the eye d, to enable the arm to turn upon the part c' and be prevented from turning when upon the part c'', as described.

A. G. SIMPSON.
